UNITED STATES PATENT OFFICE.

FELIX EMILE VALOIS, OF HAVERHILL, MASSACHUSETTS, ASSIGNOR TO HAMEL SHOE MACHINERY COMPANY, OF LYNN, MASSACHUSETTS, A CORPORATION OF MASSACHUSETTS.

SHUTTLE.

1,074,758.

Specification of Letters Patent.

Patented Oct. 7, 1913.

Application filed November 22, 1912. Serial No. 732,989.

To all whom it may concern:

Be it known that I, FELIX EMILE VALOIS, a citizen of the United States, residing at Haverhill, county of Essex, State of Massachusetts, have invented a certain new and useful Improvement in Shuttles, of which the following is a specification, reference being had therein to the accompanying drawings.

- 10 The present invention relates to lock stitch sewing machines and more particularly to that type of lock stitch sewing machines used in the manufacture of boots and shoes and known as an outsole stitcher.
- 15 The invention relates more particularly to the shuttle and bobbin mechanism of the machine, and has for its object to provide a simple and improved means for retaining the bobbin in the bobbin-case of the shuttle,
- 20 to provide an improved tension device for the shuttle-thread, and further, to insure the drawing out of the shuttle-thread to supply slack thread for the next succeeding stitch after the setting of the stitch last
- 25 formed, all of which objects are attained by the simple construction illustrated in the accompanying drawing, and which will now be described.

The invention therefore consists of the devices and combinations of devices which will be hereinafter described and claimed.

The present invention is illustrated in the accompanying drawing, which shows in Figure 1 a front elevation of a shuttle and its bobbin and showing my improvement, connected therewith, the view illustrating in sectional view a portion of the stitched work, and the condition of the thread during the operation of the take-up in setting the stitch and before the shuttle returns to its starting position preparatory to again engaging the loop of needle thread. Fig. 2 shows a vertical sectional view taken on the line 2—2 in Fig. 1. Fig. 3 shows a front elevation of the mechanism with the shuttle in engagement with the loop of needle thread and on its way to the position shown in Fig. 1 to cause the loop of needle thread to be passed about the shuttle and the bobbin and to become interlocked with the shuttle thread. Fig. 4 shows a perspective view of the improved bobbin retaining tension applying and thread pulling guide removed. Fig. 5 shows a diagrammatic view illustrating the pull-off function of the

guide. Fig. 6 shows a vertical sectional view through the shuttle with the bobbin and retaining plate removed.

In the drawings, 1 indicates the shuttle provided with the thread engaging hook 2, and the bobbin chamber 3, having the central post or spindle 4 to receive the bobbin 5, all of these parts except in so far as may be hereinafter set forth being of the usual and ordinary construction found in lock stitch sewing machines of the type hereinbefore referred to.

It will be understood by those skilled in this art, that the shuttle is mounted in a circular race, it having a peripheral rib 6 arranged to engage a guiding groove in the circular race, and that by suitable mechanism the shuttle 1 is caused to reciprocate back and forth about a central axial line for the purpose of causing the hook 2 to engage the loop of needle thread as it is drawn back by the needle and to carry said loop of needle thread over and about the bobbin, the travel of the shuttle in one direction being about to the point shown in Fig. 1 at which point the loop of needle thread may be drawn out of the hook 2 by the take-up mechanism of the machine and which by a further pull draws the loop of needle thread, and the shuttle thread with which it is engaged, into the work, as shown in Fig. 1. When the shuttle has reached the point shown in Fig. 1, its movement is reversed and it returns to its starting position which is approximately the position shown in Fig. 1, with the hook elevated and in position so that when it starts to move toward the loop of needle thread the hook will engage said loop as shown in Fig. 3. Thus, as before stated, the shuttle has what might be called a circular reciprocating motion, and is generally referred to as a circularly moving shuttle.

The bobbin 5 has a central aperture 7 arranged to be fitted upon the stud or spindle 4, and in order to retain the bobbin within the bobbin chamber 3, I have provided a retaining plate 8 having at one end an elongated recess 9 arranged to engage an undercut projection or head 10 formed at the outer end of the post 4. The retaining plate 8 at its opposite end is bent at right angles, as shown at 11, and is provided with a spring latch arranged to be inserted in a recess 12 formed in the shuttle 1, the spring 110

latch being constructed to frictionally engage the walls of the recess, and thus hold the locking plate 8 with its slot 9 engaged beneath the head 10 of the post 4. This detachable retaining plate 8 effectually holds the bobbin 5 in its chamber, but permits the free turning of the bobbin about the post 4. The spring latch may be of any suitable construction, but as shown in Figs. 2 and 4 of the drawing, it comprises the outwardly curved spring arms 13, securely fastened to the part 11 of the plate 8. These spring arms are normally spaced apart a greater distance than the diameter of the entrance of the aperture 12 and when forced through the aperture 12 will be slightly compressed.

At its rear end the aperture 12 is enlarged as shown at 14, in Fig. 2 forming a shoulder 15 so that when the arms 13 reach the enlarged portion 14 of the aperture 12, they will spring outwardly and engage the shoulder 15, thus firmly securing the plate 8 in its locking position.

The thread *t* leads from the bobbin through an aperture 16 which connects with the opening 12, and as shown in Figs. 2 and 4 the thread *t* passes out through the openings 16 and 12 over the part 11 of the plate 8 and is led through a hole 17 formed in the part 11 near its upper end, and thence the thread passes beneath the plate 8 and out through the thread guide 18 formed in the up-turned end 19 of the plate 8. On its way to the thread guide 18 the thread passes under a suitable tension device which to a certain extent resists the withdrawal of the thread from the bobbin and thus prevents the overrunning of the bobbin, as the thread is drawn therefrom. This tension device comprises a spring 20 fastened at its rear end 21 to the under side of the plate 8 and having at its opposite end an offset 22 arranged to clamp the thread against the under face of the plate 8. Thus the spring 20 produces a continuous and invariable tension on the thread.

For the purpose of insuring that a certain amount of shuttle thread shall be drawn off for the next stitch, I have as will be noted, offset the thread guide 18 from the axis about which the shuttle 1 is oscillated, and this is clearly shown by the diagram in Fig. 5. The axis of oscillation of the shuttle is represented at *a* and the thread guide 18 moves about this axis with the shuttle, the range of movement about the axis illustrated by the full and dotted line small circles shown at *r* and *r'* in Fig. 5, so that the take-up of the sewing machine when the parts are in the position shown in Fig. 1, draws downward upon the thread *t* thus drawing the loop *t*² into the work in the manner shown in the completed lock shown in Fig. 1, thus drawing all the slack of the

shuttle thread into the work. When the shuttle starts backward in the direction shown by the arrow in Fig. 1 to resume its starting position it carries the thread guide from its lowermost position shown by the dotted lines *r'* in Fig. 5 to its highest position shown by the full lines *r* in Fig. 5, and as the thread *t* is taut between the thread guide 18 and the work, as the shuttle starts its return movement this movement of the thread guide necessarily results in the thread being drawn from the bobbin, thus providing slack thread for the next stitch.

It will be noted that the end 19 which carries the thread guide 18 is raised or elevated from the surface of the bobbin or shuttle, as shown clearly in Fig. 2, thus causing the thread *t* as it leads from the guide 18 to be effectively held away from all the moving parts of the bobbin and shuttle, and this I regard as an additional important feature of my invention.

It is thought that the operation of the device will be fully understood by those skilled in the art from the foregoing description and that a further description of its operation is unnecessary.

What I claim is:

1. A circularly moving shuttle, having a bobbin chamber therein one side of which is open, a central post for the bobbin, and a retaining plate located on the open side of the bobbin chamber, said retaining plate being detachably secured to the post at one end and detachably secured to the shuttle at the other end.

2. A circularly moving shuttle having a bobbin chamber therein, a central post for the bobbin, a retaining plate engaging the post at one end and the shuttle at the other end, and a tension spring on the said plate.

3. A circularly moving shuttle having in one face an open bobbin chamber, a post for the bobbin projecting centrally from the base of the bobbin chamber, a detachable retaining plate located on the open side of the bobbin-chamber, said retaining plate having at one end a slot for engaging the head of the post and at its opposite end a compressible latch for engaging a recess in the shuttle.

4. A circularly moving shuttle having in one face an open bobbin chamber, a post for the bobbin projecting centrally from the base of the bobbin chamber, a detachable retaining plate having at one end a slot for engaging the head of the post and at its opposite end a compressible latch for engaging a recess in the shuttle and a thread guide carried by said retaining plate.

5. A circularly movable shuttle, a bobbin chamber in one face thereof, a post projecting centrally from the base of the bobbin chamber, a detachable latch plate having at one end means for engaging the post and at

- its opposite end spring members and a recess in the shuttle outside of the bobbin chamber for receiving the spring members of the latch plate.
5. A circularly movable shuttle, a bobbin chamber in one face thereof, a post projecting centrally from the base of the bobbin chamber, a detachable latch plate having at one end means for engaging the post and at 10 its opposite end means for engaging a recess in the shuttle, a tension spring secured to the said plate for engaging the bobbin thread and a thread guide.
7. In combination a circularly movable 15 shuttle, a bobbin chamber therein, a post in said bobbin chamber for receiving the bobbin, a detachable latch plate having means at one end for engaging the post and a detachable connection with the shuttle at its 20 opposite end, a tension spring carried by the
- latch plate to bear upon the bobbin thread and a thread guide carried by said latch plate and offset with relation to the axis of oscillation of the shuttle.
8. In combination a circularly movable 25 shuttle, a bobbin chamber therein, a post in said bobbin chamber for receiving the bobbin, a detachable latch plate having means at one end for engaging the post, and a detachable connection with the shuttle at its 30 opposite end and a thread guide carried by said latch plate adjacent the post engaging end and elevated above the outer face of said plate.

In testimony whereof I affix my signature, 35
in presence of two witnesses.

FELIX EMILE VALOIS.
